ATTORNEY

UNITED STATES PATENT OFFICE.

HENRY MCKINNIE, OF PITTSBURGH, PENNSYLVANIA.

BURNER.

Application filed January 23, 1926. Serial No. 83,269.

My invention consists of an improvement in burners for the combustion of gaseous fuel for heating. The object in view is to provide a burner of simple cheap construction in which means are provided for effecting a very thorough and complete admixture of the gas and air prior to combustion, and to effect such combustion immediately thereafter.

10 For such purpose I provide a closed chamber of coniform shape having means for introducing a properly proportioned admixture of gas and air at the bottom, and having a perforated cover, constructed and adapted to operate as hereinafter described.

Referring to the drawings;

Fig. 1 is a perspective view showing the burner complete from the exterior.

Fig. 2 is a central vertical section on the 20 line II—II of Fig. 1.

Fig. 3 is a cross section on the line III—III of Fig. 2.

Fig. 4 is a detail view of a modified form of initial mixer.

25 The body of the burner which is essentially a mixing chamber consists of an outer enclosing sheet metal wall 2 of coniform shape having a closed sheet metal bottom 3 fixedly connected with the lower edge of wall 2 by crimping or otherwise as at 4.

The wall 2 tapers from a maximum diameter at the outer edge of bottom 3 upwardly to the top where it is provided with a perforated covering 5, of sheet metal, 35 wire gauze, or the like.

The proportions of the mixing chamber as thus constructed are substantially as shown in the drawings and in one typical instance which has given excellent results 40 in practice, the maximum diameter at the base is 6", the reduced diameter at the top 3½" and the vertical height 11".

These proportions should be adhered to approximately in larger or smaller sizes, dependent on the volume of gas to be consumed, and any variations in the three dimensions noted should be proportionate with substantially the same taper of coniform wall 2.

50 Gas and air in combination are introduced upwardly at the central portion of bottom 3 by delivery pipe 6 leading upwardly through a fitting 7 from any suitable preliminary mixer 8.

55 In the construction shown in Figs. 1 and

2 the mixer 8, known as a Stewart mixer, is provided with an adjustable air control valve 9 adapted to increase or decrease the air inlet opening through the intervening annular space 10.

60 Gas is introduced into the middle of the mixer in the usual way by supply pipe 11 regulated by control valve 12 from any suitable source of supply. The amount and pressure of the gas will regulate its suction 65 action on the air so that the proportions of the desired mixture may be easily and accurately regulated, as will be readily understood.

As thus constructed, the combined gas and 70 air in proper proportions is introduced centrally of the base of the burner and passes upwardly into the interior 13 thereof, in the form of a middle expanding column.

Such column immediately expands outwardly against the lower portion of wall 2 and bottom 3 and with a general upward movement through the burner chamber toward the outlet cover 5. The resulting reaction, effecting complete admixture of the 75 gas and air, occurs within the chamber 13 during such movement through the upwardly diminishing space thereof, the effect of which is to constantly reduce the cross area 80 of the contained volume as it ascends.

85 Due to such action of the tapered wall 2 there is a constant and increasing reaction toward the center, together with a somewhat turbulent circulation of the mixture from the base upward toward the top.

90 The result of such action is that the fuel mixture upon arriving immediately below the perforated top 5 is in a compacted intimately associated condition with a very thorough and even admixture of the gas and 95 air.

A further effect is that due to the momentum of the mixture, the internal pressure, and the steadily diminishing diameter of the containing wall, the resulting mixture 100 emerges through the outer perforations of cover 5 with a pressure materially increased over that of the pressure at the larger base portion, and with a speed and resulting height of flame which is capable of accurate 105 control by valve 12 and adjustment of the mixture valve 9.

110 In operation, the mixture ascends within the steadily decreasing cross area of the casting 2, and passes outwardly through the

outer perforations of the top 5. Due to the closed bottom 3 and the absence of any compensating additional air to the mixture within the casing, there is a central limited 5 down draft produced, or a reverse suction, at the middle, as indicated in Fig. 2.

The result is that the combustion of the mixture immediately above the perforated top is in the form of an annular ring of 10 flame, which tapers towards the top, with a middle noncombustible zone.

The effect in use is to produce an even 15 smooth flame, with the greatest heat at its outer portion, and with a middle relatively cooler section, so that the perforated top is protected against destruction, in contrast to the ordinary Bunsen burner, where the central jet is constantly of the highest heat.

The ignition occurs immediately above 20 the perforated top 5 and results in perfect and complete combustion with resulting heat of the highest possible degree.

In Fig. 4 I show another form of standard preliminary mixer 8^a in which the gas is introduced by pipe 11^a and air by openings 10^a of fixed area, the mixture entering 25 chamber 13 of the burner by the central delivery pipe 6^a as already described.

The invention is adapted to the application 30 of heat to any practicable use, and due to the fact that all of the combustion occurs above the perforated top, there is no de-

struction or deterioration of any of the metal parts below such level.

I am aware that various forms of burners 35 have been utilized with perforated tops and concentric walls, with more or less air supply through the bottom, but believe I am the first to utilize in a burner, an entirely closed mixture chamber of the kind shown 40 and above described, in which the original mixture issues from the minor diameter at the top through a perforated covering.

As noted, the device may be variously 45 changed or altered in construction, size and different details within the scope of the following claim.

What I claim is:—

In a fuel mixing burner, the combination 50 of an upwardly tapering frusto-conical sheet metal casing having its maximum diameter bottom portion provided with a flat transverse closed bottom wall, a gas and air mixture pipe secured to and extending upwardly through the central portion of the 55 bottom wall and slightly above its inner surface, a gas supply pipe leading thereto with an intervening adjustable air supply mixer, and a circular flat perforate outlet top cover 60 extending across the minimum diameter delivery end of the burner.

In testimony whereof I hereunto affix my signature.

HENRY McKINNIE.
